(57) **CLAIM**

The ornamental design for a set of electrodes on a perforated backing sheet, as shown and described.

DESCRIPTION

FIG. 1 is a top front perspective view showing a set of electrodes on a perforated backing sheet in accordance with our new design;

FIG. 2 is a bottom rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top front exploded view thereof with the electrodes removed from the perforated backing sheet; and, FIG. 10 is a top front perspective and partially exploded view thereof as it may appear with two of the electrodes removed and the sides of the backing sheet removed along the perforations.

The short bolded broken lines on the backing sheet represent perforations and are part of the claimed design. The longer broken lines on the backing sheet depict unclaimed environmental subject matter and form no part of the claimed design. The shorter broken lines on the removable electrodes also depict unclaimed environmental subject matter and form no part of the claimed design.

The set of electrodes on a perforated backing sheet is shown with a symbolic break in its length. The appearance of any portion of the article between the break lines forms no part of the claimed design.
